UNITED STATES PATENT OFFICE.

JOHN C. McLEAN, OF CLEVELAND, OHIO, ASSIGNOR TO THE McLEAN TIRE & RUBBER COMPANY, OF CLEVELAND, OHIO, A CORPORATION OF OHIO.

DESIGN FOR A TIRE.

6,300.

Specification for Design. Patented Sept. 14, 1920.

Application filed March 19, 1920. Serial No. 367,211. Term of patent 14 years.

To all whom it may concern:

Be it known that I, JOHN C. McLEAN, a citizen of the United States, residing at Cleveland, in the county of Cuyahoga and State of Ohio, having invented a new, original, and ornamental Design for a Tire, of which the following is a specification, reference being had to the accompanying drawings, forming a part thereof.

In said drawing, Figure 1 is a plan view of the tire embodying my new design and Fig. 2 is a vertical section through the tire.

I claim:

The ornamental design for a tire substantially as shown.

JOHN C. McLEAN.
